UNITED STATES PATENT OFFICE

CRANDALL Z. ROSECRANS, OF PHILADELPHIA, PENNSYLVANIA, ASSIGNOR TO LEEDS & NORRIS COMPANY, OF PHILADELPHIA, PENNSYLVANIA, A CORPORATION OF PENNSYLVANIA

ELECTRICAL PRECIPITATOR

Application filed June 26, 1929. Serial No. 373,806.

My invention relates to the electrical precipitation of finely divided particles of matter, as of vapor, from a gas, and particularly from a gaseous stream flowing, for example, 5 to analyzing apparatus.

My invention resides in a precipitator of improved construction particularly suited for use with a source of unrectified alternating current of high potential, and more specifically, it comprises a tubular electrode member, through which the stream of gas or vapor passes, supported by a metal chamber, preferably grounded, with a wire-like electrode extending axially of the tubular electrode and 15 mechanically and electrically connected to the metal supporting structure or chamber.

My invention further resides in the methods, system and features of construction and arrangement hereinafter described and 20 claimed.

For an illustration of one of the forms my invention may take, reference is to be had to the accompanying drawing:

At its lower end the tubular member 1, is 25 provided with a gas inlet 2 and at its upper end with a gas outlet 3. Disposed upon the exterior of the tube between the gas inlet and outlet is an electrode 4, preferably of metal foil or other conductive coating to insure intimate contact between the adjacent faces of 30 the electrode and tube. The inner electrode 5 preferably a fine wire of suitable material, as platinum, is supported at the upper end of the tube by a plug 6 of suitable insulating 35 material as glass, and extends substantially axially of the tube, the lower end thereof being held by an electrically conductive supporting member 7 projecting inwardly from a collecting chamber 8, which may be of 40 metal, as iron.

The open upper end of the chamber 8 is threaded to receive a plug 9 through which the open, lower end of tube 1 extends, a sealing ring 10, of heavy packing material, preferably impregnated with grease, for example, closing the chamber to atmosphere. From the lower end of the chamber 8 there extends a pipe 11 having a U bend in which liquid 12 45 collects providing a trap or seal. 50

The electrodes 4 and 5 are directly connected to the secondary 13 of a step-up transformer 14 whose primary 15 is connected to a commercial power source of ordinary frequency and voltage, for example, a 60 cycle 55 110 volt line. It is desirable to ground one of the electrodes and I prefer to ground the inner electrode 5 by a connection from the metal structure of the chamber 8 to earth E.

It is characteristic of my invention that the precipitator electrodes are directly connected to a source of unrectified alternating current, the electrostatic field between the electrodes reversing at line frequency. To attain efficient precipitation with this circuit arrangement, the precipitator is so constructed that the charged mist particles travel across the gas stream into contact with a collecting surface, as the electrode 5, or the inside of tube 1, before reversal of polarity of the electrodes. 60

In the specific type of apparatus shown, the distance between the electrodes 4 and 5 is so small that charged particles in the stream traverse the distance between their original position to a collecting surface, that is either to wire 5, or the inside of tube 1, during the time of one-half cycle. When the frequency of the impressed voltage is 60 cycles, and potential of or about 15,000 volts impressed upon the electrodes, a tube of about three-quarter inch inside diameter is suitable. The length of electrode 4 and consequently of the region in which the gas stream is subjected to the action of an electric field is sufficiently great to insure substantially complete precipitation, for example to within .1 per cent. The tube 1 is preferably of lead glass or other semi-conductive material to obtain large potential drop between the electrode 5 and the interior surface of the tube. In effect 75 80 85

the tube 1 adjacent the metal foil 4 is itself an electrode, the glass conducting appreciable current at the high potentials involved. To avoid excessive losses, the length of tube 1 90 from the edges of outer electrode 4 to the nearest conductor of opposite polarity is suitably great.

In my co-pending application Serial No. 390,351, filed Oct. 9, 1928, there is described 100

a system in which the precipitator is utilized to remove SO_3 , or sulphuric acid mist, from a stream of SO_2 .

From a gas stream whose SO_2 content is to be determined, there is drawn by suction a continuous sample which passes through inlet 2, upwardly through precipitator tube 1, and outwardly through outlet 3 to suitable SO_2 analyzing apparatus. As the gas stream passes upwardly through tube 1, the sulphuric acid mist particles collect upon the electrode 5 and on the inner surface of tube 1, and run down into the chamber 8. The acid drain leg comprised of the tube 11 is dimensioned so that a liquid seal at the U-shaped bend 16 is maintained with the desired sub-atmospheric pressure within chamber 8; for example, the pressure in chamber 8 may be 25" of water below atmospheric. During operation, the liquid drips from the lower opening of the pipe as the acid collects in chamber 8.

If it is desired to ascertain the proportion of sulphuric acid mist, a definite volume must be passed through the precipitator, the precipitate washed, and a titration made. To increase the precipitating capacity, particularly for purposes other than analysis which require larger volumes or quantity of gas, a suitable number of precipitators may be arranged in multiple.

While I have described my precipitator as being utilized to remove particles of mist from the gas stream, it will be understood the particles may be of a finely divided solid. Further it will be appreciated that my invention is not limited to the specific construction shown, but is of breadth commensurate with the scope of the appended claims.

I claim:

1. An electric precipitator comprising a tube of semi-conductive material, a conductive coating on the exterior and intermediate the ends thereof, a wire electrode, metallic structure supporting said electrode and said tube substantially spaced from said conductive coating, and means connecting said metallic structure and said wire electrode to earth, means for producing an electric difference of potential between said coating and said wire electrode, and means for directing a stream containing finely divided particles, to one end of said tube for passage through the electric field therein.

2. An electrical precipitator comprising a tubular electrode, a wire-like electrode extending axially thereof, metal structure supporting said tubular electrode and insulated therefrom, means mechanically and electrically connecting an end of said wire-like electrode to said metal structure, means for producing an electric difference of potential between said electrodes, and means for directing a stream containing finely divided particles to the electric field between said electrodes.

3. An electrical precipitator comprising an insulating tube, a wire-like electrode extending axially thereof, a conductive coating on said tube, a metal chamber receiving the lower end of said tube and substantially spaced from said coating thereon, means mechanically and electrically connecting the lower end of said wire-like electrode to said metal chamber, means for producing an electric difference of potential between said wire-like electrode and said conductive coating, and fluid inlet and outlet conduits opening into said tube on opposite sides of said conductive coating, whereby fluid passing through the tube traverses the field between said coating and said wire-like electrode.

4. An electrical precipitator comprising a tubular electrode, a wire-like electrode extending axially thereof, a closed metal chamber supporting said tubular electrode and in communication with the interior thereof, a fluid inlet conduit opening into said tubular electrode above said chamber, a fluid outlet opening into said tubular electrode more remote from said chamber than said inlet, and means mechanically and electrically connecting the lower end of said wire-like electrode to said metal chamber, and means for producing an electric difference of potential between said electrodes, the fluid stream passing through the field between said electrodes in flowing from inlet to outlet.
